(57) **CLAIM**

I claim the ornamental design for an outsole for a shoe, as shown and described.

DESCRIPTION

FIG. 1 is a bottom perspective view of an outsole for a shoe in accordance with the new design;

FIG. 2 is bottom view thereof;

FIG. 3 is a right side view thereof;

FIG. 4 is a left side view thereof;

FIG. 5 is a front view thereof;

FIG. 6 is a rear view thereof.

FIG. 7 is a cross sectional view taken along line 7—7 shown in FIG. 4;

FIG. 8 is a cross sectional view taken along line 8—8 shown in FIG. 2;

FIG. 9 is a cross sectional view taken along line 9—9 shown in FIG. 2; and,

FIG. 10 is a cross sectional view taken along line 10—10 shown in FIG. 2.

The broken line showing a curvilinear shape in the arch area of FIG. 1, along with the parallel broken lines around the partial periphery of FIGS. 1 & 3–7 represent the boundaries of the design; with neither the lines themselves, nor the areas within them forming any part of the claim.
